UNITED STATES PATENT OFFICE.

JOHN P. BROOKS, OF CASTLETON, NEW YORK.

LACING-EYELET FOR SHOES.

946,595.

Specification of Letters Patent. Patented Jan. 18, 1910.

Application filed December 26, 1908. Serial No. 469,312.

To all whom it may concern:

Be it known that I, JOHN P. BROOKS, a citizen of the United States, residing at Castleton, in the county of Rensselaer and State of New York, have invented certain new and useful Improvements in Lacing-Eyelets of Shoes; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in lacing eyelets for shoes, leggings, &c., and the object of the invention is to produce a simple and efficient device of this nature, and consisting of a double concaved lacing contact surface for the lacing, the surfaces extending about the marginal edge of the upper to prevent friction between the lacing and the edge of the upper.

The invention consists further in the provision of an eyelet for shoes, leggings, etc., so constructed as to form a double concaved lacing contact which is adapted to extend about the edge of the upper of a shoe or of a legging and serve to prevent the parts of the article to which the eyelet is fastened from buckling and affording means whereby the number of eyelets used may be reduced and produce the same effect as where a larger number is employed, which is customary with lacing eyelets as now made.

The invention consists further in various details of construction, and arrangements of parts as will be hereinafter more fully described and then specifically defined in the appended claims.

I illustrate my invention in the accompanying drawings, which, with the letters of reference marked thereon form a part of this application and in which,

Figure 1 is a perspective view showing an upper of a shoe equipped with my improved lacing devices. Fig. 2 is an enlarged detail view of one of the eyelets. Fig. 3 is a plan view of the eyelet and Fig. 4 is a perspective view, enlarged. Fig. 5 is a side elevation of the eyelet attached to the upper of a shoe.

Reference now being had to the details of the drawings by letter A designates an eyelet made of a piece of metal, having winged portions B, each of which is concaved and

curved rearwardly, each wing extending beyond the under surface of the flat surface of the eyelet, and each designed to extend about the edge of the upper of a shoe, legging or other article to which it is applied. It will be noted that each of said wings is continuous with the wall of an eye C formed transversely to the length of the eyelet, and that said wall is convexed upon its inner lacing bearing surface. By this construction it will be observed that each end of the opening of said eye, flares outwardly trumpet shaped, thus offering a convexed pulley like bearing surface for a lacing, no matter in which direction the lacing may be drawn through the eye.

Another and important advantage, it will be observed, which is afforded by the present invention consists in the manner in which the curved wings of the eyelet engage about the marginal edge of the lacing, holding the edge engaged by said wings rigid and serving to prevent buckling between the eyelets. By having the wings thus engage the marginal edges of the upper, a considerably less number of eyelets are required to hold the edges properly laced and which is considered an item of economy in the manufacture of shoes.

Projecting from one face of the flat portion of the eyelet, is the eyelet D, similar to the usual eyelets used upon shoes, and which after being passed through the upper of a shoe, is designed to be clenched about the marginal edge of the hole through which it is passed, thus securely holding the device to the upper of the shoe. It will be noted that when the eyelet is clenched to the shoe, it will be located a sufficient distance from the edge of the upper, that there will be little likelihood of the eyelet tearing out, which frequently occurs, when the eyelets are located nearer the edge of the upper, and when strain comes upon same.

After a shoe has been equipped with the eyelets described, and in the manner set forth, the lacing is strung in the eyelets, in a zigzag manner, and by pulling upon the ends of the string, the edges of the upper of the shoe may be drawn together, without the edges of the eyelets interfering with one another. It will also be observed that the concaved surfaces of the wings, against which the lacing bears, extend about the edges of the upper, and the string is prevented from direct contact with said edges, hence saving

considerable wear upon the lacing. When the lacing is inserted through the eyelets, the concaved surfaces of the wings are nearly obscured, and a shoe having a neat appearance is produced.

By the provision of an eyelet made as shown and as herein described, an article is produced, which may be easily and automatically picked up by machinery and 10 fastened to the upper of the shoe, and which is a great desideratum in the production of a practical device of this nature.

What I claim to be new is—

1. A lacing eyelet for shoes, made of a 15 piece of sheet metal and provided with laterally extending concaved wings which are curved longitudinally and bent to extend about and engage the edge of the upper of a shoe, means for receiving the lace, and means 20 for fastening the eyelet to the shoe.

2. A lacing eyelet for shoes, made of a piece of sheet metal and having a transverse opening for the reception of a lacing, laterally extending concaved flaring wings curved

longitudinally and bent so as to extend about 25 the edge of the upper of a shoe, the bent up part of said metal formed into a transverse lacing receiving eyelet merging into said flaring wings and forming a continuous and flush lacing bearing surface through the eyelet and length of the wings and bent portions thereof, and means for fastening the device 30 to a shoe.

3. A lacing device for shoes, made of a sheet of metal, having a flat portion merging 35 into outwardly flaring curved wings bent to extend over and engage the edge of an upper and terminating in a substantially cylindrical outlined lace-receiving eyelet having flared ends and of less length than the width 40 of said flattened portion.

In testimony whereof I hereunto affix my signature in the presence of two witnesses.

JOHN P. BROOKS.
